UNITED STATES PATENT OFFICE

2,528,667

LOOP ANTENNA

Carl A. Raabe, Chicago, Ill., assignor to American Phenolic Corporation, Chicago, Ill., a corporation of Illinois

Application January 19, 1946, Serial No. 642,258

2 Claims. (Cl. 250—33.67)

1

This invention relates to insulated wire and is more particularly concerned with the provision of an insulated wire adapted for use in the manufacture of loop antennas for home and portable radios.

Heretofore, it has been the practice in the manufacture of loop antenna wire to first braid a cotton jacket over the wire and then to impregnate the covered wire with a suitable plastic material. The present invention contemplates the provision of a loop antenna wire covered with a suitable dielectric material formed with means for interlocking engagement of adjacent loop convolutions when the insulated wire is spirally wound upon itself to form a loop antenna.

This invention further contemplates the provision of one form of insulated wire having an extrudable dielectric jacket provided with longitudinally extending ridges and grooves and flat parallel side walls, said ridges and grooves being formed for interlocking engagement when the insulated wire is wound upon itself to form a loop antenna. After winding the insulated wire into the form of a loop antenna, the several convolutions thereof may readily be secured together by means of a heat sealing operation. A bearing support is then molded around a portion of the loop antenna to support same.

This invention further contemplates the provision of another form of insulated wire in which the dielectric material is provided with tongues and grooves for interlocking engagement of adjacent convolutions when the wire is wound upon itself to form a loop antenna.

This invention also contemplates the provision of another form of insulated wire comprising a plurality of copper conductors enclosed by an extruded dielectric of substantially channel-shape with side flanges for line engagement with the leg portions of an adjacent convolution when the wire is wound upon itself to form a loop antenna.

This invention embodies other novel features, details of construction and arrangement of parts which are hereinafter set forth in the specification and claims and illustrated in the accompanying drawing wherein:

Fig. 1 is a fragmentary front elevational view showing a loop antenna as formed from insulated wire embodying features of this invention.

Fig. 2 is a perspective view illustrating the construction and manner in which one form of insulated wire is wound upon itself to form a loop antenna.

Fig. 3 is a perspective view showing a modified

form of insulating wire in which the dielectric is formed with a tongue and groove for interlocking engagement of adjacent convolutions.

Fig. 4 is a perspective view illustrating another form of this invention in which a plurality of conductors are disposed within a channel-shaped dielectric, said dielectric being provided with side flanges for line engagement with leg portions of an adjacent convolution when the insulated wire is spirally wound upon itself to form a loop antenna.

Referring now to the drawings for a better understanding of this invention and more particularly to Figs. 1 and 2 therein, an insulated wire 6 is shown as comprising a copper conductor 7 which is covered by a suitable dielectric material 8. In the manufacture of the insulated wire, the dielectric material 8 is extruded over the conductor 7 and formed with a longitudinally extending ridge 9 and a longitudinally extending groove 10. The dielectric material may also be formed to provide flat parallel side walls 11 and 12 to facilitate the construction of loop antennas as hereinafter set forth.

In forming a loop antenna 13 of the type illustrated in Fig. 1, the insulated wire 6 is spirally wound upon itself by employing a suitable arbor, not shown, with the ridges 9 and recesses 10 of adjacent convolutions in aligning engagement, as illustrated in Fig. 2. After the winding operation, the several convolutions of the wire 6 are adapted to be secured together by heat sealing same transversely of the loop along the side walls 11 and 12 and at spaced intervals about the circumference of the antenna, as indicated at 14. During the heat sealing operation, the adjacent side edges of the convolutions are thus spot sealed together to provide a loop antenna construction in which the several convolutions of the insulated wire 6 will

not readily be separated. However, it is contemplated that the several convolutions of wire forming the loop antenna may be secured together by means of strips coated with adhesive. In the final assembly of the loop antenna, it is contemplated that a bearing support 16 formed of suitable dielectric material, such as the type of dielectric material 8 employed in the wire 6, may be molded in position to enclose a portion of the loop antenna.

It will thus be seen that an insulated wire of the type illustrated in Fig. 2 may be spirally wound upon itself without difficulty to form a loop antenna having flat sides suitable for bonded engagement by means of either a heat sealing operation or adhesive strips to prevent

dislocation of the several convolutions, and that a bearing support may readily be molded around a segment of the antenna thus formed to complete the assembly of the antenna.

Fig. 3 shows a modified form of insulated wire 6a comprising a copper conductor 7 having a dielectric material 18 extruded thereover. In this form of the invention, the dielectric material is formed with longitudinally extending tongues 19 and grooves 21 disposed on diametrically opposed sides of the dielectric for interlocking engagement of adjacent convolutions of the wire 6a when same is spirally wound upon itself to form a loop antenna.

Fig. 4 illustrates another modified form of insulated wire 6b comprising a plurality of conductors 22 enclosed in the base portion 23 of a substantially channel-shaped dielectric 24. A pair of flanges 26 extend outwardly in spaced parallel alignment from the base portion 23 to form therewith a recess 27 to receive the legs 28 of the dielectric when the insulating wire is spirally wound upon itself to form a loop antenna.

While this invention has been shown in several forms, it is obvious to those skilled in the art that it is not so limited but is susceptible of various changes and modifications without departing from the spirit and scope of the claimed invention.

I claim as my invention:

1. In a loop antenna, an electric conductor, insulation completely enclosing said conductor throughout its length to form an insulated cable, an elongated continuous projection formed upon one side of said insulation substantially coextensive with the length of the cable, the insulation on the opposite side of said conductor being provided with an elongated continuous indentation substantially coextensive with the length of said cable, said cable being arranged in substantially spiral form comprising a plurality of convolutions and with adjacent convolutions disposed in interlocked contact with each other, the projection of

one convolution in interengaging registry with the indentation of the adjacent convolution.

2. In a loop antenna, an electric conductor, insulation completely enclosing said conductor throughout its length to form an insulated cable, an elongated continuous projection formed upon one side of said insulation substantially coextensive with the length of the cable, the insulation on the opposite side of said conductor being provided with an elongated continuous indentation substantially coextensive with the length of said cable, the cross-sectional shape of said insulation throughout the length of the cable being substantially uniform, said cable being arranged in substantially spiral form comprising a plurality of convolutions and with adjacent convolutions disposed in interlocked contact with each other, the projection of one convolution in interengaging registry with the indentation of the adjacent convolution.

CARL A. RAABE.
